NONREFILLABLE CLOSURE FOR BOTTLES
AND LIKE CONTAINERS

Manuel Diaz Diaz, Habana, Cuba, assignor of
sixty one-hundredths to Alberto Calas Oquendo,
Habana, Cuba.

Application November 6, 1942, Serial No. 464,714
In Cuba October 2, 1942

1 Claim. (Cl. 215—21)

This invention relates particularly to the non-refillable closure for bottles and like containers, forming the subject-matter of my co-pending United States patent application Serial No. 457,270, filed September 4, 1942, and it has for its object to provide an improvement therein consisting in eliminating the packing ring fitted within the container neck and holding in position the disc provided with a central hole and a cylindrical portion which serves as a seat for the solid valve of smaller diameter than said disc and rests freely on said disc, said elimination being due to the present difficulty in obtaining a packing material, like cork, which although satisfying the conditions required for making a tight closure, when in permanent contact with a high quality liquid, such as liquor, also tends to impurify it.

The improvement forming the subject-matter of this invention further consists in substituting for the disc provided with a central hole and a cylindrical portion a device made of plastic material in the shape of a cylindrical cup having a central hole at its bottom portion and an upper horizontal annular flange adapted to seat through an intermediate packing washer on the upper edge of the container neck, the bottom portion of the cup serving as a seat for the loose disc valve, whereby a more simple closure is provided which is also sanitary by reason of the fact that the liquid is not in direct contact with any packing material capable of being crumbled or corrupted by the action of liquid humidity.

The invention is described with reference to the figures of the accompanying drawing, of which:

Fig. 1 is a diametral vertical section view of a bottle neck provided with the improved non-refillable closure of this invention, in its raised or sealed position.

Fig. 2 is a horizontal section view on line 2—2 of Fig. 1.

Fig. 3 is a perspective detailed view of the closure cover partly cut away.

Fig. 4 is a detailed perspective view of the holed disc secured in fixed position under the cover.

Fig. 5 is a detailed perspective view of the freely movable valve operating within the closure.

Fig. 6 is a detailed perspective view of the device in the shape of a cup which has a hole at its bottom portion and an upper horizontal annular flange and which carries therein the freely movable valve and rests through its flange on the upper edge of the container.

Fig. 7 is a similar section to that of Fig. 1, showing the container neck in the liquid discharge position.

In the drawing, 1 indicates a bottle neck which has adjusted at its mouth portion a device of plastic material in the shape of a cylindrical cup 2 having a central hole 3 at its bottom and a horizontal annular flange 4 at its upper edge by means of which and the interposition of a packing washer 5 it rests on the upper edge of the container 1. The inner space of cup 2 serves as a lodge for a freely movable valve consisting of a solid disc 6 of a diameter somewhat smaller than the inner diameter of the cup cylindrical body to always permit the flow of liquid thereabout in any inclined position of the bottle.

Outside the bottle neck 1 is adjusted on a shouldered peripheral portion 7 projecting therefrom, a cover 8 made of glass or any other plastic material, which has an upper section 8' of a reduced diameter to form a plain annular portion 9 adapted to hold under the latter a disc 10 made of glass or another plastic material which is secured between said annular portion 9 of the cover and the annular flange 4 of cup 2. Said disc 10 has a central hole 11 and four smaller holes 12 disposed in circumferential arrangement about the central hole 11, and the disc 10 has at its lower face four projections in the shape of a point 13 disposed alternately to the holes 12, the function of said projections being to prevent the disc 6 forming the freely movable valve from adhering or sticking to the lower face of the disc 10 in the inclined position of the bottle.

The reduced section 8' of the cover is open at its top and near its middle height it has integrally therewith a partition 14 which has at its portion bordering the inner surface of section 8' four equidistant openings 15 not vertically registering with the holes 12 of lower disc 10, to which end the latter is secured in a fixed position within the cover 8 by means of a pointed projection 16 formed at any portion of the lower face of annular portion 9 of the cover and engaging a recess 17 formed on the upper surface of the disc 10.

The section 8' of the cover has at its outer surface a thread 18 to threadedly receive a threaded cap 19 preferably made of metal and which fits on the upper edge of the section 8' of the cover through an intermediate disc 20 of a compressible material, such as cork, to prevent leaking of the liquid in the sealed position of the cap 19.

The cover 8 is inviolably secured on the bottle

neck 1 by means of an annular layer of a molten material 21 which is inserted in the space formed between the recessed portion 7' of the bottle neck beneath the shouldered peripheral portion 7 of the bottle and the lower portion of the cover 8. The molten material may be in the nature of a sealing-wax or the like.

The operation of this closure is exactly as the operation of the closure forming the subject-matter of my co-pending United States patent application Serial No. 457,270, only that the present closure has the advantage that a packing ring being not provided for holding the seat for the freely movable valve within the bottle neck and the cup device serving as a seat for the freely movable valve being made of a plastic material which is not capable of being crumpled or corrupted by the humidity action of the liquid as this is discharged, the liquid will never be contaminated, but it will always keep clean.

What I claim is:

A non-refillable closure for a bottle comprising

5 a cap having a skirt portion surrounding the neck of the bottle, a top portion of reduced diameter, a shoulder overlying the mouth of the bottle between the skirt portion and top portion, a flanged cup having an opening in the bottom, a 10 perforated disc having teats directed towards the interior of the cup, the disc and flange of the cup being seated between the shoulder of the cap and the mouth of the bottle in circumferential engagement with the skirt, means for locking the disc against rotation relatively to the shoulder, a flat disc valve loosely slidable on the bottom of the cup and adapted to cover the opening, and a second perforated flat disc integral with the top portion of the cap, the perforations of said last named disc being out of alignment with those of the first named disc, 15 said cap, discs, cup and valve forming a self-contained structure suitable for application to the neck of the bottle by the skirt portion of the cap.

MANUEL DIAZ DIAZ.
